US0D1031175S

(12) **United States Design Patent** (10) **Patent No.:** **US D1,031,175 S**
(45) **Date of Patent:** **** Jun. 11, 2024**

(54) **MASK**

(71) Applicant: **CHANCE ZHUHAI HENGQIN INTERNATIONAL TRADING CO.,**
Zhuhai (CN)

(72) Inventor: **In Kei Chan**, Macau (CN)

(73) Assignee: **CHANCE ZHUHAI HENGQIN INTERNATIONAL TRADING CO.,**
Zhuhai (CN)

(**) Term: **15 Years**

(21) Appl. No.: **29/923,915**

(22) Filed: **Jan. 3, 2024**

(51) LOC (14) Cl. **29-02**

(52) U.S. Cl.

USPC **D29/108**

CLAIM

The ornamental design for a mask, as shown and described.

DESCRIPTION

FIG. 1 is a front perspective view of a mask, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the mask, which form no part of the claimed design.

1 Claim, 8 Drawing Sheets
